UNITED STATES PATENT OFFICE.

JAMES HENNESSEY, OF MARION, INDIANA, ASSIGNOR OF ONE-HALF TO
JAMES ROWAN, OF MARION, INDIANA.

SHOE-LACE FASTENER.

SPECIFICATION forming part of Letters Patent No. 726,289, dated April 28, 1903.

Original application filed October 12, 1901, Serial No. 78,473. Divided and this application filed March 17, 1902, Serial No. 93,503. (No model.)

To all whom it may concern:

Be it known that I, JAMES HENNESSEY, a citizen of the United States, residing at Marion, in the county of Grant and State of Indiana, 5 have invented a new and useful Improvement in Shoe-Lace Fasteners, of which the following description, taken in connection with the accompanying drawings, is a specification, like characters representing like parts in all 10 the figures.

My invention relates to fasteners or holding devices for the ends of lacings used in any kind of wearing-apparel, but more particularly for lacings for boots, shoes, gloves, 15 and like articles.

The object of my invention is to provide a fastener which shall be simple in construction, effective in use, cheap of production, practical, and susceptible of ornamentation.

Particularly, my object is to provide a fastener to be used in connection with a "single-lace" fastening for closing all kinds of apparel in connection with which it may be found practicable.

To the above ends, therefore, the invention consists in the parts, features, and combinations hereinafter described and claimed.

In the drawings, Figure 1 is a perspective view of a shoe, showing my fastener applied thereto, this view showing the fastener in place on the shoe when the latter is properly laced. Fig. 2 is a vertical sectional view of the fastener on the line $x-x$ of Fig. 1, showing the manner of applying the lace to the 35 pin or bar of the fastener. Fig. 3 is a plan showing a portion of a glove with my fastener and lace in place, the lace being slack and the fastener hanging away from the glove to illustrate the manner of applying the same.

Primarily, it is to be observed that the contemplated use of the fastener is in connection with articles of apparel which have a slit or opening to be closed by drawing the adjacent edges together and which have, usually, adjacent the edges of the slit or opening a plurality of holding devices, such as eyelets or hooks, adapted to receive the lace, cord, or ribbon.

Referring now to the details of my invention, the fastener in the form contemplated

by my invention and clearly shown in Fig. 2 of the drawings consists of a concavo-convexed head or body portion c' , plain or ornamental, having as a securing medium a transverse pin or bar e , secured thereto in any 55 suitable way and adapted to hold the looped end of the lace. This fastener is to be used in connection with an ordinary but extra eyelet h' , disposed as hereinafter described. It is to be noted that the head c' is substantially flat on the bottom or concaved side e^2 , providing a rim e' to enable it to lie flat upon the article, and that the pin or bar is so secured as to bridge the concavity e^2 and be well within the same, so that the head may 60 be drawn down closely to the shoe or other article and make a neat appearance. To enable this latter effect to be secured, the concavity of the head is made in diameter slightly greater than that of the eyelet h' employed. 70 The concavo-convexed head or body portion c' has two functions, the first being to provide a cover or shield for the looped end of the lace, as shown in Fig. 1, and the second being to provide a base or foundation or 75 setting for some ornamental figure, jewel, or design, it being clear that said body part may be etched or otherwise ornamented or may be so carved or constructed as to afford a setting for a jewel or ornament. 80

The details of my fastener having been described, it now remains to note the manner of using the same. The shoe, glove, or other article is provided with an extra hole, disposed at a suitable point outside the line of 85 the usual holding devices m , preferably near the lower end of the latter, as shown in Figs. 1 and 3. In such hole the eyelet h' is secured, and the end of the lace m' is then looped about or tied to the pin or bar e , as shown in 90 Fig. 2—e. g., by forming a small loop in its end, drawing the same over the bar e between the latter and the head c' , and then inserting its other end in the loop and drawing the lace tightly about the bar e . The free end of the 95 lace will then be passed inwardly through the eyelet h' , as shown in Figs. 1 and 3, then outwardly through the adjacent eyelet of the series of holding devices, and the shoe or glove subsequently fastened as provided. 100

When the lace is drawn tight and finally secured, the fastener c' will be drawn into place closely against the article and will completely cover and hide the eyelet h' , as shown in Fig. 1.

At the upper end of the slit or opening the shoe, &c., is provided with a "final fastener" of any suitable form, that shown in Figs. 1 and 4 of the drawings consisting of two devices $a a$, one disposed on each side of the slit and parallel with the edges of the article. This final fastener is made the subject of an application filed of even date herewith, Serial No. 98,504, and which forms a division of an application filed by me October 12, 1901, Serial No. 78,473. The fastener of this application is likewise a division of my application last referred to.

Having thus described my invention, what

I desire to claim and secure by Letters Patent is—

A fastener for articles of apparel consisting of a concavo-convexed head having a flat bottom, or rim, surrounding the concavity, and also having a straight bar, or pin, located well within, and extending from side to side of, the concavity, so as to bridge the same, whereby said fastener is specially adapted to be used with a single lace and may be drawn closely to, and lie flat upon, said article, substantially as described.

In testimony whereof I have hereunto signed my name in the presence of two subscribing witnesses.

JAMES HENNESSEY.
